UNITED STATES PATENT OFFICE.

ROBERT C. MORTON, OF BALTIMORE, MARYLAND.

LOCOMOTIVE STEAM-PIPE.

1,322,260.

Specification of Letters Patent.

Patented Nov. 18, 1919.

Application filed January 14, 1919. Serial No. 271,060.

To all whom it may concern:

Be it known that I, ROBERT C. MORTON, of the city of Baltimore, in the State of Maryland, have invented a certain new and useful Improvement in Locomotive Steam-Pipes, of which improvement the following is a specification.

The object of my invention is to provide means, of simple and inexpensive construction, and ready applicability in locomotives of any of the several present standard types, whereby accumulation of water in the cylinders, and damage resultant therefrom, may be effectually prevented.

15 The improvement claimed is hereinafter fully set forth.

In the operation of locomotive engines, it frequently occurs that the enginemen will carry water at too high a level in the boiler, 20 with the result that a considerable quantity is worked through the engine cylinders and the lubrication thereof is flooded out. Again, it is often the case, when locomotives are standing some little time in round- 25 houses or yards, that, by reason of leakage past the throttle valve, steam passes into the cylinders, and the resultant accumulated condensate causes their breakage when the locomotive is moved, thereby involving considerable expense for repair, and the loss 30 of service of the locomotive while repairs are being made. These objectionable results, which are familiar to those in charge 35 of locomotive operation, will be eliminated by the application of my invention.

In the accompanying drawings: Figure 1 is a side view, partly in elevation, and partly in section, of the forward portion of a locomotive engine in which my invention 40 is applied; Fig. 2, a vertical transverse section through the smoke box; and, Fig. 3, a horizontal section through one of the steam pipes, on the line $\alpha\alpha$ of Fig. 1.

In the practice of my invention, referring descriptively to the specific embodiment thereof which is herein exemplified, I combine, with each of the steam pipes, 1, through which, as in the ordinary practice, steam is conveyed from the dry pipe of the 45 boiler, either directly or through a super-heater header, 5, to the valve chest, 3, and cylinders, 4, a water receptacle, 2, which extends longitudinally, from its upper end, to or near the location in its length at which 50 it passes through the smoke box, 6. The top of the steam pipe is downwardly curved, in

the usual manner, and, at the bottom of its curvature, is fully open to the top of the water receptacle, and the remainder of the length of the pipe which is within the 60 smoke box, is offset from, or out of axial line with, the curved top portion, as clearly shown in Fig. 1. The steam pipe being ordinarily formed of cast iron, the water receptacle, 2, is preferably, as shown, formed 65 integral with it, but, if desired, its length, below the curved top portion of the steam pipes, may be made separate from, and secured to, the main body of the pipe. Continuously open communication between the 70 curved top portion of the steam pipe and the offset main body thereof, is instituted by a steam delivery passage, 2^a, formed in the wall of the pipe adjoining the water receptacle, at, or adjacent to, the bottom of 75 the curved top portion, and a deflecting plate, 2^b, which is curved upwardly and away from the water receptacle, projects from the lower edge of the passage, 2^a.

A water discharge or drain pipe, 7, leads 80 from the bottom of the water receptacle to a suitable point of discharge below the adjacent cylinder, 4, at which point it is connected to an automatic drain valve, 8, which may be of any suitable known construction, 85 and which, as it is not, in and of itself, claimed as of my present invention, is not herein at length described. A manually operable water discharge cock, 9, is fitted in a branch pipe, 7^a, leading out of the main discharge pipe, 7, adjacent to the lower end thereof, said cock being opened and closed, as desired, by an arm, 9^a, coupled to the bar, 10, which operates the ordinary cylinder cocks, 11, so as to be opened and closed coincidently with said cocks.

In the operation of the appliance, water that may be carried, with the steam, into the steam pipe, is deposited by gravity, in the water receptacle, and the steam, thus cleared 100 of water, passes through the steam delivery passage, 2^a, into the main body of the steam pipe, and thence to the valve chest and cylinder. The deflecting plate, 2^b, prevents water from entering the main body of the pipe. 105 Water which may accumulate in the water receptacle while the locomotive is standing, will be discharged therefrom by the automatic drain valve, 8, and, when running, may be discharged by the cock, 9, when the latter is opened, for the purpose, coincidently with the opening of the cylinder cocks.

It will be seen that the cost of construction and maintenance of my invention is in-
considerable; that it involves no perceptible
obstruction of the volume of the smoke box;
5 and that it is applicable in connection with
either outside or inside steam pipes, with-
out interference with, or modification of,
other members contained in the front end
of the locomotive. The practical value and
10 importance of the capacity which it affords
of preventing accumulation of water in the
cylinders, will be readily recognized by
those who have experienced the detrimental
results of such accumulation.

15 I claim as my invention and desire to se-
cure by Letters Patent:

1. In a locomotive, the combination with
the boiler, valve chest and cylinder, of a
20 steam pipe extending from the boiler to the
valve chest, a water receptacle on the pipe,
means for separating the water from the
steam, means for directing the water to the
receptacle, a discharge cock for said recep-
tacle, a discharge cock for the cylinder, and
25 means common to both of said cocks for op-
erating the same.

2. In a locomotive, the combination with
the boiler and valve chest thereof, of a

steam pipe connecting the boiler and chest,
said pipe being located in and following sub-
stantially the contour of the wall of the
smoke box, a steam separator comprising a
water receptacle, and means for separating
the water from the steam and directing the
water to the receptacle, located on the for-
ward side of the pipe and extending longi-
tudinally thereof, the transverse width of
the separator being no greater than the
transverse diameter of the pipe, whereby the
draft through the smoke box will not be in-
40 terfered with.

3. In a locomotive, the combination with
a boiler, valve chest and cylinder, of a steam
45 pipe extending from the boiler to the valve
chest, a water receptacle on the pipe, means
for separating the water from the steam,
means for directing the water to the recep-
tacle, a drain pipe leading from the lower
50 portion of the water receptacle to a point of
discharge exterior to the smoke box, and a
discharge valve controlling the outer end of
said drain pipe.

ROBT. C. MORTON.
